UNITED STATES PATENT OFFICE

92,273

DESIGN FOR A RING

Otto E. Strohm, Chicago, Ill.

Application November 16, 1933, Serial No. 49,760

Term of patent 3½ years

To all whom it may concern:

Be it known that I, OTTO E. STROHM, a citizen of the United States, residing at Chicago, in the county of Cook and State of Illinois, have invented a new, original, and ornamental Design for Rings, of which the following is a specification, reference being had to the accompanying drawing, forming part thereof.

Figure 1 is a view showing a development of the blank from which a ring is made, and showing my new design.

Fig. 2 is a perspective view of a ring, showing my new design.

Fig. 3 is an edge view of the same; and
Fig. 4 is a side view of the same.

I claim:

The ornamental design for a ring substantially as shown.

OTTO E. STROHM.
